UNITED STATES PATENT OFFICE.

LOUIS E. FULLER, OF NEW YORK, N. Y., ASSIGNOR, BY MESNE ASSIGNMENTS, TO
A. B. DICK COMPANY, OF CHICAGO, ILLINOIS, A CORPORATION OF ILLINOIS.

PROCESS FOR FORMING STENCIL-SHEETS.

1,101,269.

Specification of Letters Patent. Patented June 23, 1914.

No Drawing.

Application filed July 20, 1910. Serial No. 572,928.

To all whom it may concern:

Be it known that I, LOUIS E. FULLER, a citizen of the United States, and a resident of the city of New York, in the county and State of New York, have invented certain new and useful Improvements in Processes for Forming Stencil-Sheets, of which the following is a full and complete disclosure.

My invention relates to sheets coated or 10 impregnated with suitable substances normally impervious to ink, but adapted when struck or impressed by the characters of a typewriter, or similar device, to permit the passage of ink wherever the sheet has been 15 struck or impressed, and thus enable the sheet to be used as a stencil for the reproduction of the characters impressed thereon.

Heretofore it has been the usual custom 20 to form stencil sheets by coating a suitable paper with an impervious coating of wax or similar substance, and to form the necessary characters in or on the sheet by striking the wax coat with the characters of an ordinary typewriter, the intention being to 25 express the wax from the sheet wherever it is struck by the character or characters, and thus enable the sheet to be used as a stencil. This method of forming stencils has, however, proved unsatisfactory, because with 30 such sheets it is necessary to remove the wax in order to secure clear and uniform copies, and this is not possible with an ordinary typewriter or any impression device available for such use. This method is also unsatisfactory, because the wax on the stencil 35 sheets deteriorates under ordinary changes of temperature, and the sheets have a comparatively short life.

The object of my improved process is to 40 overcome these difficulties and defects, to produce a sheet the coating of which is not subject to temperature changes, and which may be used to produce a large number of copies, and which when impressed or struck by the characters of an ordinary typewriter, 45 will produce smooth and slightly copies.

Other advantages and objects of my invention will appear from the following description.

50 In practising my invention, I take a sheet of thin open lace-like paper, such as Japanese Yoshino paper, and coat it with a colloidal composition having certain hygroscopic properties, and adapted when exposed 55 in a moist atmosphere, or to water or

moisture, to swell or expand, so as to produce a coating having a cellular structure, which when struck or impressed with the desired characters and dried, will produce smooth and slightly copies, even though the material has not been cut out by the impression character. A suitable composition for this purpose may be formed by mixing a protein, such as gelatin, with a coagulating agent, such as potassium dichromate and a tempering agent, such as glycerin or sugar, or a mixture of the two. One method for forming this coating is as follows: I first prepare a concentrated solution of gelatin, sugar, acetic acid and water. The proportions of these ingredients may be reasonably varied, with the result that the compound will be thicker or thinner. The solution which I have found to be the best and most useful is as follows: gelatin one part; white sugar, one part; glacial acetic acid pure, one part; glycerin, two parts; water, two parts; all by weight; potassium dichromate in crystals enough to color the compound a deep yellow. The gelatin should first be broken into pieces of a convenient size and dissolved in the acetic acid and water, a gentle heat, such as a water bath, being applied, if it is desirable to effect solution in a shorter period of time. The sugar and glycerin are then added and the whole thoroughly mixed, so that the ingredients are completely blended and dissolved. The potassium dichromate, preferably powdered crystals, is then added to the extent of as much as the solution will dissolve, or at least enough to color the compound a deep yellow. The whole is then filtered by suitable means.

The solution may be applied to the paper by laying the sheet on a smooth non-absorptive surface, as a plate of glass, and flowing the solution thereover by means of a brush, a dim light being desirable, in this coating operation as in the operation of preparing the solution as above described. The sheet is then suspended to dry, and when dried it is exposed to daylight or other suitable light. Within a shorter or longer time, dependent upon the intensity of the light, the sheet will change in color to a grayish green or lavender, such change being due to the reduction of potassium dichromate to chrome alum and coagulation of the gelatin. By such exposure and reduction, the compound is rendered non-plastic and substantially in-

soluble in water, hot or cold, except that it will soften slightly under the influence of moisture and is hygroscopic. It is also rendered proof against all neutral solvents 5 and against concentrated alkaline and dilute acid solutions. It is also proof against oils and greases, and all solvents of the same.

The foregoing composition is that described in my pending application Serial 10 No. 540,078, and I make no claim herein to the composition as such. It may be varied in the manner specified in my said application, and other equivalent compositions may be used in carrying out my present process.

15 In carrying out my process, after the sheet has been dried as above described, it is subjected to moisture by being stored in a humidor, or in any suitable manner, and the moisture swells or expands the coating 20 on the sheet, so that it assumes a cellular structure, and yet is impervious to ink. The sheet is then placed in a typewriter or any suitable impression device, and characters impressed thereon. It is not necessary to 25 cut out the coating, but only to break down or crush the cellular structure. The sheet is then allowed to dry, after which it may be placed in a frame and an inked roller passed thereover, whereupon the ink will 30 pass freely through the portions of the sheet which have been impressed, and reproduce upon an underlying blank sheet the characters which said portions represent. The softening heretofore mentioned of the 35 material in the paper is temporary in the sense that it is produced for the particular purpose of forming the characters, the paper being practically dry in its ordinary condition, and after being moistened and the 40 characters formed in it, will again become comparatively dry, so that it may be conveniently used with a stencil without becoming limp and sticky, as it would be if permanently moistened, while at the same 45 time drying causes the severed edges of the material to shrink and enlarge the opening.

While I have described only one way of carrying out my improved process, I am aware that modifications and changes may 50 be made therein by those skilled in the art, without departing from the spirit of my invention or the scope of my claims.

What I claim is:

1. The process of forming a stencil sheet 55 which consists in impregnating a sheet of fibrous material with a colloidal substance,

rendering said substance normally non-plastic but capable of being temporarily softened, by treating the same with a coagulant and drying the sheet so impregnated, 60 substantially as described.

2. The process of forming a stencil-sheet which consists in impregnating a sheet of fibrous material with a colloidal substance, rendering said substance normally non-plastic but capable of being temporarily softened, by treating the same with a coagulant and a tempering agent and drying the sheet so impregnated, substantially as described. 65

3. The process of forming a stencil-sheet which consists in impregnating a sheet of fibrous material with a colloidal substance, rendering said substance normally non-plastic but capable of being temporarily 75 softened, by treating the same with a chromic coagulant and drying the sheet so impregnated, substantially as described.

4. The process of forming a stencil-sheet which consists in impregnating a sheet of 80 fibrous material with a colloidal substance, rendering said substance normally non-plastic but capable of being temporarily softened, by treating the same with a chromic coagulant and a tempering agent and drying the sheet so impregnated, substantially 85 as described.

5. The process of forming a stencil-sheet which consists in impregnating a sheet of 90 fibrous material with protein and rendering the protein insoluble in water by applying a chromic coagulating agent and exposing it to light, substantially as described.

6. The process of forming a stencil-sheet which consists in impregnating a sheet of 95 fibrous material with protein and a suitable tempering agent, and rendering the protein insoluble in water by applying a chromic coagulating agent and exposing it to light, substantially as described. 100

7. The process of forming a stencil-sheet which consists in impregnating such sheet, at a single operation, with a composition including a protein, such as gelatin, a chromic coagulating agent and a tempering agent, 105 and exposing the sheet to light to coagulate the coating thereon and render it dry but hygroscopic, substantially as described.

LOUIS E. FULLER.

Witnesses:

EDWARD M. BENTLEY.

DISCLAIMER.

1,101,269.—*Louis E. Fuller*, New York, N. Y. PROCESS FOR FORMING STENCIL-MACHINES. Patent dated June 23, 1914. Disclaimer filed December 4, 1916, by the assignee, *A. B. Dick Company*.

Enters its disclaimer as follows, to wit:

1. It disclaims any and all process or processes which include impregnating a fibrous sheet, except such as involve impregnating a thin, open, lacelike paper such as Japanese Yoshino paper or its equivalent.
2. It disclaims any and all process or processes of forming stencil-sheets except such as, employing the said patented invention, are used, or adapted or intended to be used, for conversion into stencils by impact or pressure, such, for example, as the action of the type of a writing-machine.
